UNITED STATES PATENT OFFICE.

CHARLES W. WALSTROM, OF STAFFORD, NEBRASKA.

STOVEPIPE HOLDER.

Application filed March 20, 1926. Serial No. 96,140.

This invention is a stove pipe holder for holding and retaining a stove pipe in proper position in the chimney flue.

The object of the invention is to provide a simple and efficient device for the purpose described and which may be easily operated for locking the pipe into the flue or for releasing the pipe, as may be desired.

In the drawing—

10 Figure 1 is a longitudinal section through a stove pipe and chimney, showing this device in operative position;

15 Figure 2 is a transverse section through the elbow of the pipe, showing the device operatively mounted therein;

Figure 3 is a right side elevation of the pipe elbow showing the hand wheel for winding up the wire onto the spool;

20 Figure 4 is a left side elevation of the pipe elbow showing the ratchet wheel and ratchet for holding the wire as wound onto the spool;

Figure 5 is a detail of the wire spool;

Figure 6 is a detail of the hand wheel.

25 In combination with the upper horizontal length of stove pipe 1 as inserted in the pipe hole 2 of the chimney 3, and the elbow 14, the invention comprises toggle levers or grapples 4 pivoted together at 5, the free 30 ends of the levers being formed into hooks 6 adapted to engage the inner face 7 of the chimney flue at either side of the pipe hole 2, as shown. A brace 8 is pivotally attached at 9 to one of the levers 4, and the opposite 35 end of the brace passes slidingly through a slot 10 in the opposite lever 4. There is a stop 11 mounted medially on the brace 8, and a coil spring 12 is mounted over the brace 8 between the stop 11, and the slotted lever 4 normally acts to spread the levers 4 asunder. Side plates 13 are mounted exteriorly upon the sides of the elbow 14 and transversely aligned shaft holes 15 are cut 40 through these plates and through the walls 45 of the elbow. A spool shaft 16 having a ratchet wheel 17 rigidly attached to one end, is provided, the opposite end of the shaft having a threaded bolt hole 18 formed longitudinally therein; and a wire spool 19 is 50 also provided, the same having a longitudinal shaft hole 20. The wire spool 19 is adapted to pass within the elbow 14 and be

positioned transversely therein in alignment with the holes 15, and the spool is of such a length that its ends will not bind against the inner walls of the elbow. The spool shaft 16 is then passed through the holes 15 of the plates and elbow and through the shaft hole 20 of the wire spool and the opposite protruding end of the shaft 16 is squared to engage a hand wheel 21 having a squared axial hole 22, and the wheel is then locked upon the end of the shaft 16 by means of the washer 23 and bolt 24 passed into the threaded hole 18. Aligned 55 bolt holes 25 are formed through the spool 19 and spool shaft 16 and a bolt 26 is passed through these holes and locked in place by a nut 27. Thus the spool is firmly anchored 60 to the spool shaft. A spring set pawl 28 is pivoted at 29 upon a plate 13 adjacent the ratchet wheel 17, the pawl being placed in engagement with the said ratchet wheel 65 so as to prevent its retrograde movement. A tension wire 30 is attached at 31 to the point 5 of the connected levers 4, and the wire is then run through the pipe 1 and is attached at its outer end to the bolt 26 of the spool 19. By rotating the hand wheel 70 21 in the direction permitted by the pawl 28, the wire 30 is readily wound upon the spool 19, thereby effectively drawing the elbow 14 and pipe 1 snugly into place against the chimney. The pipe may be as readily 75 released by disengaging the pawl 28, unwinding the wire from the spool, pulling out the pipe 1 and disengaging the levers 4 from the chimney flue.

80 While I have herein described a certain specific manner and method of constructing and assembling the elements of my invention, it is understood that I may vary from the same in minor details, not departing from the spirit of my invention, so as best to construct a practical device for the purpose intended, as defined in the appended claim.

I claim:—

85 The combination, with a stove pipe and elbow positioned in a flue opening, of a device of the kind described, comprising toggle levers pivoted together so as to form an approximate A-shape, and having provided at their free ends semi-circular hooks, an ar- 90 95 100

cuate brace pivoted to one of the said toggle levers and adapted to pass slidably through a slot provided in the other toggle lever, a stop provided medially on said brace, a spring mounted on said brace and adapted to engage the said stop and said toggle lever provided with said slot, whereby said spring

acts to force asunder said toggle levers, and means for utilizing said toggle levers to position said stove pipe and elbow in conjunction with said flue opening. ¹⁰

In testimony whereof I affix my signature.

CHARLES W. WALSTROM.
